UNITED STATES PATENT OFFICE.

GEORGE W. DORMAN, OF EVERETT, WASHINGTON, ASSIGNOR TO THE SUMNER IRON WORKS,
OF EVERETT, WASHINGTON, A CORPORATION OF WASHINGTON.

SHINGLE-MACHINE.

No. 885,327.

Specification of Letters Patent. Patented April 21, 1908.

Application filed October 13, 1906. Serial No. 338,793.

To all whom it may concern:

Be it known that I, GEORGE W. DORMAN, a citizen of the United States, residing at Everett, in the county of Snohomish and State of Washington, have invented a new and useful Shingle-Machine, of which the following is a specification.

The invention relates to improvements in shingle machines.

10 The object of the present invention is to improve the construction of shingle machines, and to provide a simple, inexpensive and efficient machine capable of automatically feeding a shingle block to the saw, and of 15 cutting the shingles with the tips and the butts alternately at the top and bottom of the block.

20 A further object of the invention is to provide a machine of this character, which, when there is a knot, or other imperfection in a shingle block, nearer to one end than the other of the same, will be capable of cutting the shingles so that the knot or other imperfection will continuously occur at the tip or thin end.

25 With these and other objects in view, the invention consists in the construction and novel combination of parts hereinafter fully described, illustrated in the accompanying 30 drawings, and pointed out in the claims hereto appended; it being understood that various changes in the form, proportion, size and minor details of construction, within the scope of the claims may be resorted to without departing from the spirit or sacrificing 35 any of the advantages of the invention.

In the drawings:—Figure 1 is a side elevation of a shingle machine, constructed in accordance with this invention. Fig. 2 is an 40 enlarged side elevation of one end of the shingle machine. Fig. 3 is an end elevation on the same scale as Fig. 2. Fig. 4 is a perspective view of one end of the machine, illustrating the arrangement of the feed 45 mechanism. Fig. 5 is a side elevation partly in section of the eccentric device for setting or reversing the feed mechanism. Fig. 6 is an end view of the eccentric device partly in section. Fig. 7 is a detail perspective view 50 of the eccentric device, the means for actuating the same, and the means for throwing the eccentric device out of operation.

55 Like numerals of reference designate corresponding parts in all the figures of the drawings.

1 designates the base of the main frame, designed to be made of metal, and which may be of any preferred construction to secure the desired strength and weight. The main frame is provided with an upwardly extending substantially rectangular portion 2, and it is provided at the top and bottom thereof with longitudinal guides or ways 3 and 4, preferably consisting of projecting flanges and receiving a reciprocating carriage 5. 60 The carriage 5, which is provided with the means hereinafter described for clamping a shingle block, is movable toward and from a circular saw 6. The bottom of the carriage is provided at its ends with integral casings 7 65 in which are mounted grooved rollers or wheels 8, and the latter run upon the flange of the bottom guide or way 4, which forms a track for the carriage. The top of the carriage is provided with a longitudinal groove 70 9 to receive the flange of the upper guide or way 3. The inner end of the carriage, or the end nearer the saw, is connected by a suitable pivot 10 with one end of a connecting rod or bar 11, which extends to the upper end of an 80 oscillatory lever 12, and which is connected with the same by a suitable pivot 13. The ends of the connecting rod or bar may be secured to the carriage and to the oscillatory lever in any desired manner. The said lever 85 is fulcrumed at its lower end on a suitable pivot 14.

The oscillatory lever is actuated by an eccentrically arranged pivot or wrist pin 15, mounted on an arm of a gear wheel 16 and 90 forming a crank element. The eccentrically arranged pin or pivot 15 passes through a suitable opening of a slide 17, consisting of a block and movable longitudinally of the oscillatory lever 12. The slide 17, which may be 95 constructed in any desired manner, is provided with a suitable opening to receive the oscillatory lever, and it slidably connects the same with the gear wheel 16.

The gear wheel 16, which is keyed or otherwise secured to a shaft 18, meshes with a pinion 19 of a counter-shaft 20, on which is mounted a pulley 21. The pulley 21 is connected by a belt 22 with a smaller pulley 23, which is mounted on the saw shaft or arbor 105 25. The saw shaft or arbor is designed to be connected with suitable driving mechanism, and to be provided with means for throwing the shingle machine into and out of operation. Motion is communicated from 110

the saw arbor or shaft to the gearing, which oscillates the lever 12, and the latter actuates the carriage and the means hereinafter described for feeding the shingle block.

5 The shingle block is yieldably clamped between upper and lower rolls 26 and 27, provided with spur teeth arranged at intervals, as shown, and adapted to grip the upper and lower faces of the shingle block. The spur teeth, which are arranged in annular series, project beyond the body portion of the rolls. The lower roll 27 is journaled in suitable bearings of the reciprocating carriage at the bottom thereof, and the upper roll 26 is 10 mounted in suitable bearings of a hinged clamping frame or member 28, which is provided at its ends with arms 29. The arms 29 are provided with suitable eyes or openings for the reception of a horizontal pivot or 15 pintle rod 30, which is adjustably mounted on the carriage, the latter being provided with a plurality of ears or bearings 31 for the reception of the said rod 30. The hinged frame or member 28 is adapted to swing upwardly and downwardly to engage and release a shingle block, and it is connected by a link 32 with a weighted lever 33, which yieldably maintains the roll 26 of the movable clamp frame or member 28 in engagement with the shingle block. The downward movement of the upper shingle block engaging roll is limited by a keeper 33^a, mounted at the top of the carriage and receiving the weighted arm of the lever 33. 20 The lever 33, which is fulcrumed at an intermediate point by a bolt 34, or other suitable fastening device, is provided at one of its arms with a weight 35, and its other arm is angularly bent and is connected by a rod 36 with a foot lever or treadle 37. The weighted lever 33 is located above the hinged frame or member 28, and when the foot lever or treadle 37 is depressed, the weighted arm of the lever 33 and the hinged frame or member 28 are raised. The weight is adapted to carry the upper engaging roll 26 automatically into engagement with the shingle block, when the foot is removed from the lever or treadle 37. The foot lever or treadle 37, 25 which extends longitudinally of the machine, is fulcrumed at its inner end on the saw, and a rod 36 is secured at its lower end to the lever or treadle 37 at a point between the ends thereof.

30 The upper and lower rolls are reversely rotated to feed the shingle block forwardly or outwardly, the bottom portions of the upper roll being moved forwardly or outwardly, and the top portions of the lower feed roll 27 being simultaneously moved in the same direction. The upper and lower feed rolls 26 and 27 are provided with ratchet wheels 38 and 39, having their teeth shouldered in opposite directions. The upper ratchet wheel 38 is engaged by an adjustable pawl or dog 40 of a bar or member 41, pivotally connected at its inner or rear end 42 with an upwardly extending arm 43 of an upper bell crank lever 44. The outer end of the bar or member 41 is provided with an enlargement, or head 70 45, which is bifurcated at the bottom to straddle the upper ratchet wheel 38 and in which the pawl or dog is adjustably mounted, being secured in its adjustment by a set screw 46. The pawl or dog 40, which is provided at its lower end with a tooth or engaging portion, is arranged in a slot or opening of the head or enlargement 45 of the bar or member 41. The upper bell crank lever 44 is fulcrumed at its angle on a suitable pivot 47, 75 and it has an approximately horizontal arm 48 provided with a terminal pivot 49, receiving an anti-friction roller or wheel 50. When the arm 48 is swung upward by the means hereinafter described, the bar or member 41 will be moved inwardly or rearwardly, and the ratchet wheel 38 will be rotated in a direction to feed the shingle block forwardly or outwardly. After the bell crank lever has been oscillated to feed the upper rolls 26, it is 80 automatically returned to its initial position by a spring 51, when it is free to return. The spring 51 is coiled at the inner portion of the pivot 47, and its terminals are connected respectively with the bell crank lever and 85 with a bracket 52 from which the pivot 47 extends. The bracket 52, which is securely bolted to the carriage 5, is provided with a projecting arm 53 having a threaded opening for the reception of a vertically adjustable screw 54, which is adapted to support a horizontally extending arm 48. The screw provides means for adjustably supporting the arm 48, and it thereby limits the return movement of the upper bell crank lever and 90 controls the feeding movement. 95

100 The lower feed roll 27 is actuated in its feeding movement by means of an adjustable pawl or dog 55, mounted in a slot or opening of a head or enlargement 56 of a bar or member 57. The head or enlargement 56 is bifurcated at the bottom to straddle the lower ratchet wheel 39, and the inner or rear end of the bar or member 57 is pivoted to the lower end of a depending arm 58 of a bell crank lever 59, fulcrumed at its angle on a pivot 60 of a bracket 61, which is bolted to the reciprocating carriage at a point below the upper bracket 52. The bell crank lever 59, which is actuated in its return movement by a 105 spring 62, is provided with a substantially horizontal arm 63, having a terminal pivot, which receives an anti-friction roller or wheel 64. The lower bell crank lever is constructed similar to the upper bell crank lever, the only 110 difference being in the arrangement of the arms, whereby the bars or members 41 and 57 will be reversely actuated to secure the proper rotary movement of the rolls 26 and 27 to feed the shingle block. The approxi- 115 120 125 130

5 mately vertical arm 43 of the upper bell crank lever is moved inwardly or backwardly to actuate the upper feed roll, and the approximately vertical arm 58 of the 70 lower bell crank lever is moved forwardly or outwardly to rotate the lower roll 27. The bracket 61 is provided with a horizontally projecting arm 65, which has a threaded perforation for the reception of a vertically adjustable screw 66. The screw 66 adjustably supports the arm 65 of the lower bell crank lever and composes the feeding movement of the lower roll.

10 The bell crank levers are automatically operated on the return movement or stroke of the reciprocating carriage by means of upper and lower arms 67 and 68, disposed longitudinally of the machine in the direction of the movement of the reciprocating carriage, and 75 pivoted at their outer ends 68^a and 69 to the upwardly extending portion of the main frame and provided at their inner ends with inclined portions 70 and 71, located in the path of the approximately horizontal arms 20 of the bell crank levers and presenting inclined upper faces for engagement with the said anti-friction rollers or wheels 53 and 61, and forming relatively fixed cams for actuating the bell crank levers. The arms are connected at an intermediate point to the upper 25 ends of a pair of lifting rods or bars 72 and 73, which are approximately vertical and which are connected at their lower ends to levers 74 and 75. The levers 74 and 75 are fulcrumed 30 at their outer ends on a horizontal pivot 76 of the main frame of the machine, and they are provided at an intermediate point with upwardly extending arms or portions, which are pivoted to the lower ends of the lifting 35 rods or bars.

40 The upper and lower arms 67 and 68 are adjustably supported at the limit of their downward movement by means of brackets 77 and 78, having horizontally projecting 45 arms and provided at the outer ends thereof with vertically adjustable screws 79 and 80. These adjusting screws assist in controlling the feeding movements of the upper and lower shingle block engaging rolls. The adjusting screws of the bell crank lever and the 50 arms are provided with jam nuts for locking the screws in their adjustment.

55 The levers 74 and 75, which swing upwardly and downwardly, are alternately lifted by an eccentric device, consisting of a pair of disks 81 and 82 spaced apart and mounted on a stub shaft 83, and carrying eccentrically arranged lever-engaging means, which preferably consists of anti-friction 60 rollers or wheels 84 and 85, located respectively between the disks 81 and 82, and at the inner face of the disk 82 in the space between the same and the main frame. The anti-friction rollers 84 are arranged at diametrically opposite points, and are mounted

65 on pins or pivots 86. The other anti-friction rollers or wheels 85 are located equi-distant of the anti-friction rollers or wheels 84, and by this arrangement the lifting levers 74 and 75 will be alternately raised, when the eccentric 70 device is rotated.

75 The eccentric device is rotated by means of a push rod or bar 87, extending longitudinally of the machine and adjustably connected at its inner end 88 to a short arm 89 of the oscillatory lever. The outer portion of the push rod or bar is provided with a hook shaped shoulder 90, which is adapted to successively engage a series of pins 91, extending laterally from the outer face of the disk 81 80 and located at the intervals between the anti-friction rollers and wheels 84 and 85. The outer portion of the push rod or bar 87 is slidably supported by a cam shaped arm 92 of a shaft 93, and the eccentric device is rotated one quarter of a revolution by each outward stroke of the push rod or bar, which is adapted to move inwardly or backwardly without affecting the position of the eccentric device. By this partial rotary movement of the eccentric device, the anti-friction rollers or wheels 84 and 85 are successively brought to the top of the said eccentric device and are caused to alternately lift the levers 74 and 75. When the upper arm 95 90 is raised by the eccentric mechanism, its cam portion is positioned to increase the feeding movement of the upper roll 26, which is thereby partially rotated a greater distance than the lower roll 27. When in this 100 position the shingle block will be fed outward, so that the butt of the shingle will be cut at the top of the shingle block. When the lower arm 68 is raised and the upper arm 69 lifted from the screws 79, as illustrated in 105 Fig. 2 of the drawings, the lower feed roll will be rotated in excess of the upper feed roll and the butt of the shingle block. When the eccentric device is in operation, the shingles will be cut from the block with the 110 tips and the butts alternately at the top and bottom of the block. The short arm 89, which extends upwardly from the lower end of the oscillating lever 12, is provided at its upper portion with a slot 94, in which the pivot of the inner or rear end of the push rod or bar 87 is adjustably secured. By raising and lowering the pivot of the inner or rear end of the push rod, the throw or stroke of the same may be varied.

115 When there is a knot or other imperfection in a shingle block nearer to one end than the other, the shingles may be continuously cut with the knot or imperfection at the tip by throwing the push rod or bar 87 out of 120 operation, when the arms 67 and 68 are in position for feeding the shingle block to cut a shingle with the knot or other imperfection at the tip thereof. This is effected by means of an operating lever 95, secured to the shaft 125 130

93 and adapted to partially rotate the said shaft 93 and thereby oscillate the cam shaped arm 92. When the cam shaped arm 92 is swung upwardly from the position, illustrated in Fig. 2 of the drawings, the engaging end of the push rod or bar will be lifted and maintained out of engagement with the eccentric device. The shaft 93 is journaled in suitable bearings of a bracket 96, and the outward movement of the operating lever is limited by a stop 97 of a curved guiding bar or member 98. The bracket 96, which is provided at its top with a horizontally disposed approximately U-shaped portion 99, has an upwardly extending arm 100, which is arranged at the outer edge of the outer portion of the push rod or bar to prevent any lateral movement thereof.

The eccentric device is held against accidental rotary movement by means of a brake 101, which prevents the eccentric device from being turned too far by the push rod or bar. The brake consists of a curved casting pivot at its upper end 102 by the shaft 93, and carrying a brake shoe 103, which engages the disks of the eccentric device. The brake is held yieldably in engagement with the eccentric device by means of a coiled spring 104, interposed between a substantially L-shaped arm or piece 105, and the lower portion of the brake and the pressure is regulated by an adjusting screw 106, which controls the tension of the spring.

Having thus fully described my invention, what I claim as new and desire to secure by Letters Patent, is:—

1. The combination with a saw, of a carriage, feed rolls mounted on the carriage, an oscillatory lever, means for connecting the lever with the carriage, means for operating the feed rolls embodying a push bar connected with and actuated by the said lever, devices carried by the lever for adjusting the push bar toward and from the pivotal point of the lever, and means for oscillating the lever.

2. The combination with a reciprocating carriage, of feed rolls mounted on the carriage for feeding a shingle block, mechanisms connected with the rolls for rotating the same, independently movable relatively fixed devices arranged in the path of the said mechanisms for imparting motion to the same when the carriage is reciprocated, and means for alternately operating the said relatively fixed devices for moving one of the feed rolls in excess of the other.

3. The combination with a reciprocating carriage, of feed rolls mounted on the carriage for feeding a shingle block, mechanisms connected with the rolls for rotating the same, independently movable relatively fixed devices arranged in the path of the said mechanisms for imparting motion to the same when the carriage is reciprocated, means for alternately operating the said relatively

fixed devices for moving one of the feed rolls in excess of the other, and mechanism for throwing the said means out of operation, whereby the tips of the shingles will be continuously cut from the same portion of the block. 70

4. The combination with a reciprocating carriage, of feed rolls mounted on the carriage for feeding a shingle block, mechanism connected with the rolls for rotating the same, independently movable relatively fixed devices arranged in the path of the said mechanism for imparting motion to the same when the carriage is reciprocated, and means for differentially adjusting the said relatively fixed devices for moving one of the feed rolls in excess of the other. 75

5. The combination with a reciprocating carriage, of feed rolls mounted thereon, spaced mechanism connected with the rolls 85 for rotating the same and provided with levers, independently movable pivoted arms having inclined faces for engaging the levers, and means for alternately adjusting the arms for moving one lever in excess of the other. 90

6. The combination with a reciprocating carriage, of feeding devices mounted on the carriage, pivoted arms arranged in the path of the feeding devices for actuating the same, levers connected with the arms, and means for alternately engaging the levers for adjusting the arms. 95

7. The combination with a reciprocating carriage, of spaced feeding devices mounted on the carriage, pivoted arms arranged in the 100 path of the feeding devices for actuating the same, levers connected with the arms, and rotary means having eccentrically arranged devices for alternately operating the levers.

8. The combination with a reciprocating carriage, of feeding devices mounted on the carriage, pivoted arms arranged in the path of the feeding devices for actuating the same, levers located beneath the arms, push rods connecting the arms and the levers, and rotary means for alternately engaging the levers to adjust the arms. 110

9. The combination with a reciprocating carriage, of feeding devices mounted on the carriage, pivoted arms arranged in the path 115 of the feeding devices for actuating the same, levers located beneath the arms, push rods connecting the arms and the levers, rotary means for alternately engaging the levers to adjust the arms, and adjustable means supporting the arms and limiting the downward movement of the levers. 120

10. The combination with a reciprocating carriage, of feeding devices mounted on the carriage, pivoted arms arranged in the path 125 of the feeding devices for actuating the same, levers located beneath the arms, push rods connecting the arms and the levers, rotary means for alternately engaging the levers to adjust the arms, and screws located beneath 130

- the arms and adjustably supporting the same and limiting the downward movement of the levers.
11. The combination with a reciprocating carriage, of spaced feeding devices mounted on the carriage, pivoted arms arranged in the path of the feeding devices for actuating the same, levers connected with the arms, and a rotary eccentric device embodying spaced members, and an eccentrically arranged means carried by the members for alternately engaging the levers. 70
12. The combination with a reciprocating carriage, of spaced feeding devices mounted on the carriage, pivoted arms arranged in the path of the feeding devices for actuating the same, levers connected with the arms, and a rotary eccentric device composed of spaced disks provided with anti-friction devices arranged to alternately engage the levers. 75
13. The combination with a reciprocating carriage, of spaced feeding devices mounted on the carriage, pivoted arms arranged in the path of the feeding devices for actuating the same, levers connected with the arms, a rotary eccentric device provided with means for alternately engaging the said levers, said eccentric device being also provided with eccentrically arranged projections, and a reciprocating push bar provided with means for engaging the projections for actuating the rotary eccentric device. 80
14. The combination with a reciprocating carriage, of spaced feeding devices, pivoted means located in the path of the feeding devices for actuating the same when the carriage is reciprocated, a rotary eccentric device for alternately operating the said pivoted means for moving one of the feeding devices in excess of the other, a push bar for actuating the eccentric device, and a brake yieldably engaging the eccentric device. 85
15. The combination with a reciprocating carriage, of spaced feeding devices, pivoted means located in the path of the feeding devices for actuating the same when the carriage is reciprocated, and means for adjusting one of the pivoted devices in excess of the other. 90
16. The combination with a reciprocating carriage, of spaced feeding devices, relatively fixed means arranged in the path of the feeding devices for actuating the same when the carriage is reciprocated, a rotary eccentric device for alternately adjusting the relatively fixed devices for moving one of the feeding devices in excess of the other, a push bar arranged to engage the eccentric device, and manually operated means having an arm arranged to support the push bar out of engagement with the eccentric device. 95
17. The combination with a reciprocating carriage, of spaced feeding devices, adjustable means arranged in the path of the feeding devices for actuating the same when the carriage is reciprocated, an eccentric device for operating the said adjustable means, a push bar for actuating the eccentric device, a shaft provided with means for holding the push bar out of engagement with the eccentric device, and a brake hung from the shaft and engaging the eccentric device. 100
18. The combination with a reciprocating carriage, of feed rolls mounted on the carriage, ratchet wheels connected with the feed rolls, levers also mounted on the carriage, pawls or dogs connected with the levers and engaging the ratchet wheels, pivoted arms arranged in the path of the levers for actuating the same when the carriage is reciprocated, and adjustable means for supporting the arms and for limiting the movement of the same in one direction. 105
19. The combination with a reciprocating carriage, of an oscillatory lever connected with the carriage, spaced feeding devices mounted on the carriage, pivoted means located in the path of the feeding devices for actuating the same when the carriage is reciprocated, a rotary eccentric device for alternately operating the said pivoted means to move one of the feeding devices in excess of the other, and a reciprocating push bar actuated by the said lever and provided with means for engaging the rotary eccentric device. 110
20. The combination with a reciprocating carriage, of an oscillatory lever connected with the carriage, spaced feeding devices mounted on the carriage, pivoted means located in the path of the feeding devices for actuating the same when the carriage is reciprocated, a rotary eccentric device for alternately operating the pivoted means to move one of the feeding devices in excess of the other, said eccentric device being provided at intervals with pins, a push bar connected at one end to the lever and provided near its other end with a hook-shaped shoulder for engaging the said pins, and a manually operable shaft having an arm for supporting the push bar out of engagement with the eccentric device. 115
21. The combination with a reciprocating carriage, of an oscillatory lever connected with the carriage, spaced feeding devices mounted on the carriage, pivoted means located in the path of the feeding devices for actuating the same when the carriage is reciprocated, a rotary eccentric device for alternately operating the pivoted means to move one of the feeding devices in excess of the other, said eccentric being provided at intervals with pins, a push bar connected at one end to the lever and provided near its other end with a hook-shaped shoulder for engaging the said pins, a bracket provided with an upwardly extending arm arranged to hold the push rod against lateral movement, and a manually operated shaft sup- 120
- 125
- 130

ported by the bracket and provided with an arm for holding the push bar out of engagement with the eccentric device.

22. The combination with a reciprocating carriage, of spaced feeding devices, pivoted means located in the path of the feeding devices for actuating the same when the carriage is reciprocated, a rotary eccentric device for alternately operating the pivoted means for moving one of the feeding devices

in excess of the other, and brake mechanism for engaging the rotary eccentric device.

In testimony, that I claim the foregoing as my own, I have hereto affixed my signature in the presence of two witnesses.

GEORGE W. DORMAN.
